UNITED STATES PATENT OFFICE.

ROBERT C. SCHEMMEL, OF UNION CITY, INDIANA.

FINISHING WELT.

Application filed May 8, 1929. Serial No. 361,421.

My present invention relates to improvements in welts, gimps and bindings made of leather, leather substitutes and woven fabrics for use in trimming automobile bodies and 5 tops, other vehicles, furniture, etc.

The invention comprises a finishing welt of the blind-nail type, and is in the nature of an improvement upon United States Letters Patent No. 1,528,699, issued to me under 10 date of March 3, 1925. It has for an object the production of welts having a within-contained filler strip extending across the base of the welt and its foldable body or tack-concealed member, and provided with trans- 15 versely arranged metallic strands woven into said filler strip made of pliable annealed wire, preferably copper, arranged and adapted to be folded upon themselves and to retain the welt body in its final folded 20 position without the use of other fastening means.

It has for an object also the production and introduction into a welt of a filler strip such as above indicated, which is of uni- 25 formly flat form and capable of imparting to the structure the folding features aforesaid without in the least detracting from the smooth and unbroken surface appearance of the welt.

30 With the foregoing and other objects in view, which will be apparent to persons skilled in the art to which it relates, the invention will be hereinafter described and particularly pointed out in the appended 35 claims.

In the accompanying drawings which form part of this application for Letters Patent, and whereon corresponding numerals indicate like parts in the several views:

40 Figure 1 is a perspective view, partly in section, of my improved welt;

Fig. 2 is a relatively enlarged, transverse sectional view of the welt with its wire reinforcing filler strip incorporated therein and 45 its tack-concealing body portion partially folded as it approaches operative position;

Fig. 3 is also a transverse sectional view corresponding with Figure 2, but showing the welt folded in the final operative position; and

Fig. 4 is a fragmentary perspective view showing the filler strip employed in this form of welt, including interwoven, pliable, metallic weft strands shown in dotted lines.

55 Reference being had to the drawings and numerals thereon, 1 indicates a flexible core

of any suitable material, such for example as paper, cord, rubber or other elastic material, and of any desired cross sectional form, that shown by the present illustrations being half round, and 2 indicates a longitudinal beading core also of any suitable flexible material, but preferably of tightly twisted paper cord for economy of manufacture. These two parallel members numbered 1 and 60 2 are completely enclosed or enveloped in a wrapper of suitable material, preferably a unitary strip of leather, imitation leather, or fabric of any kind, either with or without a nap of mohair or plush, according to 65 requirements of the individual job to be trimmed.

This one-piece wrapper or envelope starting at 3, completely surrounds the core 1 to form a welt body 4, as shown by the drawings. It then continues inwardly upon a 75 base line as at 5, to the beading core 2 which it surrounds and encloses to constitute a bead 6, and again crossing the structure as at 7 in parallelism, but not in contact with the 80 member 5, terminates at 8, thus constituting a two-ply welt base as shown by Figures 1, 2 and 3.

Interposed between the two-ply base members 5 and 7, is a filler strip 9 of woven material, characterized by transversely arranged and interwoven pliable strands of annealed wire 10 in a gauge corresponding with that of the remaining fabric strands which collectively make up the flat filler 90 strip 9 as a whole. The transverse wire strands 10 aforesaid, are simply woven into the filler strip as weft fabric strands instead of the usual fabric threads, and while they may be of any bendable, pliable material, 95 copper wire has been found in practice to be most satisfactory.

The filler strip 9 having been introduced in operative position, between the two-ply base members 5 and 7, continues on, normally in 100 flat form, crossing the under surface of core 1, as indicated in dotted lines by Figure 2, and is secured in this relation of parts by a line of stitches 11 as shown by Figures 1, 2 and 3.

When constructed substantially as aforesaid, the completed welt, with its wire reinforced but bendable filler strip 9, is placed upon the market in flat form, that is to say with the filler strip 9 embedded, and extending from side to side of the structure. The 110 welt is then applied and secured in flat form

to the body of a vehicle by the usual fastening tacks, such as 12, driven directly through the two-ply base and its within-contained filler strip 9, as indicated by Figures 2 and 3.
5 This accomplished, the welt body or core 1 is folded by hand of the trimmer, first into the position indicated by Figure 2, and then into its final finished position as shown by Figure 3, in which latter position it is neatly and
10 securely retained solely by agency of the transversely arranged weft wires 10, which have been doubled upon themselves in the process of folding.

Having thus described my present invention in one form of embodiment, what I now claim and desire to secure by Letters Patent is:

15 1. A finishing welt of the blind-nail type, including a base portion, a tack-concealing body portion, and an interposed filler-strip
20

having incorporated therein a series of transversely positioned pliable, metallic strands arranged and adapted to be folded upon themselves and to retain the said body portion in its final operative position.

25 2. A finishing welt of the blind-nail type, including a two-ply base portion, a tack-concealing body portion hinged to said base portion, and a filler-strip embedded in the base portion aforesaid continuing beneath the 30 body portion and having incorporated therein a series of pliable, metallic strands arranged and adapted to be folded upon themselves and to retain the said body portion in its final operative position.

3. A blind nail finishing welt having a wire-cloth filler-strip associated therewith.

In testimony whereof I affix my signature.

ROBERT C. SCHEMMEL.
